(57) **CLAIM**

The ornamental design for a channel hole pattern, as shown and described.

DESCRIPTION

FIG. 1 is a perspective view of a first embodiment of the channel hole pattern.

FIG. 2 is a bottom view of a first embodiment of the channel hole pattern.

FIG. 3 is a first end view of a first embodiment of the channel hole pattern.

FIG. 4 is a first side view of a first embodiment of the channel hole pattern.

FIG. 5 is a second side view of a first embodiment of the channel hole pattern.

FIG. 6 is a top view of a first embodiment of the channel hole pattern.

FIG. 7 is a second end view of a first embodiment of the channel hole pattern.

FIG. 8 is a perspective view of a second embodiment of the channel hole pattern.

FIG. 9 is a bottom view of a second embodiment of the channel hole pattern.

FIG. 10 is a first end view of a second embodiment of the channel hole pattern.

FIG. 11 is a first side view of a second embodiment of the channel hole pattern.

FIG. 12 is a second side view of a second embodiment of the channel hole pattern.

FIG. 13 is a top view of a second embodiment of the channel hole pattern.

FIG. 14 is a second end view of a second embodiment of the channel hole pattern.

FIG. 15 is a perspective view of a third embodiment of the channel hole pattern.

FIG. 16 is a bottom view of a third embodiment of the channel hole pattern.

FIG. 17 is a first end view of a third embodiment of the channel hole pattern.

FIG. 18 is a first side view of a third embodiment of the channel hole pattern.

FIG. 19 is a second side view of a third embodiment of the channel hole pattern.

FIG. 20 is a top view of a third embodiment of the channel hole pattern; and,

FIG. 21 is a second end view of a third embodiment of the channel hole pattern.

(Continued)

The broken lines of FIGS. 1-21 are included for the purpose of illustrating environmental structure and form no part of the claimed design.
